PULL CHAIN SOCKET

Frank E. Johnson, New Bedford, Mass., assignor
to John I. Paulding, Inc., New Bedford, Mass.,
a corporation of Massachusetts

Application November 17, 1933, Serial No. 698,444

5 Claims. (Cl. 173—354)

This invention relates to lamp sockets and more particularly to that type of sockets adapted to be operated by a chain and commonly known as pull chain sockets.

In this type of lamp sockets, the current for illuminating the lamp is controlled by a switch in which an actuating member is rotated through a fixed arc by pulling a chain attached thereto against the tension of a spring which when the chain is released returns the actuating member to its initial position. It is common in these devices to provide a bell guide through which the pull chain passes out from the switch but it frequently happens, however, when the chain is pulled to operate the switch and then suddenly released that the return movement of the actuating member pulls the chain in too far so that it becomes jammed inside the guide rendering the switch inoperative.

One of the important objects of the invention is the provision of means in a pull chain socket for locking the chain against undue inward movement so that irrespective of the way in which the pull chain is operated there will be no possibility of the chain being retracted into the switch mechanism in such manner as to affect its switch operation.

Another object of the invention is to provide simple, compact and inexpensive means for accomplishing the foregoing object.

Other objects of the invention will be more specifically set forth and described hereinafter.

My invention contemplates the provision of means for preventing any undue inward movement of the pull chain through the guide on the return movement of the switch actuating member. In its preferred form the invention consists in providing a guard member adapted to project in between the two links of the chain which lie adjacent the inner end of the guide when the actuating member is in normal position in order to prevent any further inward movement of the pull chain.

In the accompanying drawing illustrating one form of the invention, Figure 1 is a view in perspective of a pull chain socket provided with a chain guard constructed and adapted to be operated in accordance with my invention; Fig. 2 is an exploded view of the insulating body and various parts of the switch mechanism; Fig. 3 is a transverse sectional view of a portion of the switch structure showing the guard in its normal relation to the pull chain and chain guide; and Fig. 4 is a view in perspective of a guard having a notched end.

Referring to the drawing, there is shown an insulating body comprising a lower disk or block 10 and an upper disk or block 11 fastened together in spaced relation by three brackets 12, 13 and 14, the upper face of the lower block 10 being provided with suitable recesses 15, 16 and 17 and the lower face of the upper block 11 with recesses 18, 19 and 20 for receiving the turned ends of the brackets 12, 13 and 14 respectively which are fastened to the two blocks by rivets or other suitable means. The brackets 13 and 14 are each provided with a binding screw 21 and serve as terminals. The blocks or disks are made of porcelain or any other suitable insulating material. Fastened to the top face of the upper block 11 is a lamp receiving screw shell 22 of usual and well-known construction which forms one of the lamp contacts by means of the screw 23 connecting the shell to the bracket terminal 13. A central lamp contact 24 is fastened to the upper face of the block 11 within the screw shell, the latter being cut away at 25 to avoid short circuiting.

Mounted between the two blocks or disks is a switch adapted to be operated by a pull chain. The lower face of the upper block 11 is provided with an annular series of four inclines forming ratchet teeth 26, 27, 28 and 29. The two alternate teeth 26 and 28 are faced by two metallic fixed contacts 30 and 31 respectively, the contact 30 being provided with a tail connected by a rivet 32 to the central lamp contact 24 on the upper face of block 11 and the other contact 31 being an extension part of the bracket 14. For bridging the fixed contacts, a metallic contact member 35 is provided with a hole 36 and is rotatably mounted on a pin 37 interposed between the two blocks 10 and 11 with its two ends seated in recesses 38 and 39 formed in said blocks respectively. The contact member 35 has a pair of opposite radial wings 40 adapted to engage the fixed contacts 30 and 31 when turned into proper position, which wings are inclined in order to make flat engagement either with said contacts or with the ratchet teeth.

For rotating the contact member 35, an actuating member 42 in the form of a quadrant is mounted on the pin 37 below the contact member 35 and is provided on its upper face with a circular series of ratchet teeth 43 adapted to engage radial projections or fingers 44 on the said contact member. The actuating member 42 is held in a normal retracted position as shown in Figure 1 by a coil spring 45 mounted on the pin 37 and having one end fastened to the member

- 42 and the other end secured in the insulating block 10. For rotating the actuating member 42 against the tension of said spring to turn the contact member 35 a quarter revolution, a pull chain comprising balls 47 and connecting links 53 are fastened at one end to the actuating member and led out through a bell guide 48 on the bracket 12. The actuating member is provided adjacent its circumferential edge with a flange 49 right angled in cross section to form a channel for the chain, the end of which is hooked into one turned split end 50 of the flange 49. The other end of the flange is extended to form a curved tongue or guard 51, the end of which projects in between the two balls which lie adjacent the inner end of the bell guide 48 when the actuating member is in normal position. If desired, the end of the guard may be notched as shown in the guard 52 in Figure 4.
- 20 It will be observed, referring to Figure 3, that when the actuating member is in normal position the end of the guard 51 abuts that ball of the pull chain in the inner end of the guide 48 thereby acting as a stop to prevent any further inward movement of the pull chain. When the chain is pulled to operate the switch the resulting movement of the actuating member swings the guard out of the way so that it in no way interferes with that operation.
- 30 In the drawing I have shown merely the insulating body with terminals and switch operative parts since the metallic socket used to enclose these parts is of common and well known construction and the enclosure of these parts therein would be obvious to those skilled in the art.
- 35 In operating the switch, the pull chain is drawn downwardly which turns the actuating member through an arc slightly in excess of ninety degrees.
- 40 The ratchet teeth 43 on that member engage the fingers 44 on the contact member 35 and turn it with the actuating member. As the contact member is turned, its wings 40 ride up on the inclined ratchet teeth on the lower face of the insulating block 11, the spring 45 permitting this movement, until they reach the next succeeding ratchet teeth when the pressure of the spring forces the wings into flat engagement with said teeth.
- 45 On each operation of the actuating member, the contact member is moved a quarter revolution thereby either closing the circuit between the fixed contacts 30 and 31 or opening the circuit. When the pull chain is released, the actuating member is returned to its normal position, the ratchet teeth 43 sliding over the fingers 44 on the contact member. In this operation the guard travels with the actuating member and on its return movement the guard returns to its position as shown in Figure 3 to stop undue inward movement of the chain.
- 50 Although my invention is illustrated as embodied in a lamp socket, it is not to be limited thereto because it may be used in any construction which employs a pull chain for operating a movable part.
- 55 What I claim is:
1. In a device of the character described, the combination of an actuating member, a spring for holding said member in normal position, a pull

chain, comprising balls and connecting links, for moving said actuating member against the tension of said spring, a chain guide and means mounted on said actuating member and adapted, when said actuating member is in normal position, to project between the two balls of said chain adjacent the inner end of said guide to prevent further inward movement of said pull chain.

2. In a device of the character described, the combination of an actuating member adapted for rotation through a predetermined arc, a spring for holding said member in normal retracted position, a pull chain comprising balls and connecting links for operating said actuating member, a chain guide through which said pull chain leads out of said device and a curved guard mounted on said actuating member and adapted to project in between the two balls of said chain adjacent said guide for preventing undue inward movement of said pull chain when released.

3. In a switch, the combination of an actuating member mounted for rotation through a predetermined arc, a spring for holding said member in normal retracted position, a pull chain comprising balls and connecting links, said chain being attached at one end to said actuating member for moving said actuating member against the tension of said spring to operate said switch, a chain guide and a guard mounted on said actuating member and adapted, when said actuating member is in normal position, to project between the two ball links of said chain adjacent the inner end of said guide to prevent further inward movement of said pull chain.

4. In a device of the character described, the combination of a rotary contact for controlling a circuit, an actuating member mounted for rotary reciprocal movement through a limited arc for operating said contact, a spring for holding said member in normal retracted position, a pull chain comprising balls and connecting links for moving said actuating member against the tension of said spring to operate said rotary contact, a chain guide and means mounted on said actuating member and adapted, when said actuating member is in normal position, to project between the two ball links of said pull chain adjacent the inner end of said guide to prevent undue inward movement of said pull chain when released.

5. In a device of the character described, the combination of a pair of fixed contacts, a rotatable contact for bridging said fixed contacts to close a circuit, an actuating member mounted for reciprocal rotary movement through a predetermined arc for operating said rotatable contact, a spring for holding said member in normal retracted position, a pull chain comprising balls and connecting links for moving said actuating member against the tension of said spring to operate said rotatable contact, a bell guide through which said chain passes outwardly from said switch and a curved guard mounted on said actuating member and adapted, when said actuating member is in normal position, to project between the two ball links of said chain adjacent the inner end of said guide to prevent undue inward movement of said pull chain.

FRANK E. JOHNSON.
